UNITED STATES PATENT OFFICE

GLENN P. HEATH, OF GALESBURG, ILLINOIS

AIR CLEANER

Application filed July 31, 1929. Serial No. 382,350.

My invention relates primarily to devices for removing dust and other matters in suspension from a column of moving air, or gas.

One object of my invention is the provision of a device which is particularly adapted to insertion in a conduit at a point where the conduit makes a bend.

Another object of my invention is to construct and arrange the parts of the device so that instead of retarding the movement of the fluid, either gas or air, its movement will be rather assisted in its passage around the bend in the conduit, while at the same time, providing a device which will remove all or nearly all of the dust or other particles carried by the moving column of fluid.

Another object of my invention is to provide a structure where in the event that the device is neglected and becomes incapable of further dust or particle collection, no interruption to the free flow of the fluid will be produced.

Another object of my invention is the provision of a structure comprising in part a cleaning unit which is easily removed or replaced when required and further, the provision of a structure which is simple in construction and arrangement, inexpensive to produce, and efficient in action.

Other objects of my invention will be described in the specification.

The novelty of my invention will be hereinafter more fully set forth and specifically pointed out in the claims.

In the accompanying drawing:

Fig. 1 is a sectional side elevation of part of a conduit showing my cleaner installed therein.

Fig. 2 is a sectional view of Fig. 1, taken about on the dotted line 2—2 and looking diagonally upward to the left.

Fig. 3 is a perspective detail of one form of screening element used in the device.

The same numerals of reference are used to indicate identical parts in all the figures.

As illustrating one form of device embodying my invention, though without limiting myself to the precise details of construction and arrangement of parts shown and to be herein described, but availing myself of all

changes and modifications that may be made within the scope of the appended claims, I have shown a device consisting of a housing 4 which is preferably arranged as a portion of an elbow in an air or other fluid conduit, 5 being that part of the conduit which delivers the air or fluid to the cleaner, and 6 being that part of the conduit which receives the air or fluid from the cleaner. Within the housing 4 I support a frame work consisting of a plurality of slotted members 7 mounted upon a pair of end members 8, this frame work being adapted to slide on rails 9 formed within the housing 4, access to the interior of the housing being gained through any suitable door 10 (Fig. 2).

A curved screen 11 (Fig. 3) is inserted in each of the slots of the members 7, and as shown in the upper portion of Fig. 1 some or all of these screens may be provided with angular extensions 12.

As shown in Fig. 3 the screens 11 may be made of wire mesh of any desirable size of wire or spacing, or these screens may be made of sheet metal or other substance.

One use for the device would be to locate it in the cold air duct of a warm air furnace under which condition the section 5 of the duct would be the lower portion of the vertical or nearly vertical part thereof, while the section 6 would be a portion of the horizontal part of the duct leading to the air admission passage of the furnace jacket.

Air ducts as ordinarily constructed are usually joined at an angle and as the air flows through the duct there is a certain resistance set up in the bend due to the tendency of the whole column of air to continue its downward movement.

With the installation of my device, the downward moving column of air is, in a measure, divided into a number of thin horizontally arranged sheets, each of which is directed around the bend, thereby assisting rather than retarding the turning of the column of air and as this column turns, the tendency for any dust particles is to continue their linear movement and so come in contact with one or the other of the screens.

In practice it is advisable, after all the

screens have been placed in the frame, to either dip or spray the frame and screens with a relatively non-volatile odorless fluid such as an oil to assist in catching and holding the dust particles as the air passes through the device.

By arranging the centers of the various radii of the slots for the screens on a line closer to the upper or entrance edges of the screens, it will be noted that the areas between the screens are greater at their entrance edges than at the exit edges at the end of the curved portion and this construction slightly increases the speed of the movement of the air and the centrifugal force applied to the dust particles thereby more effectively removing them.

In the construction of the screens shown in the upper left portion of Fig. 1 where the extensions 12 are shown, a slight deflection of the travel of the air is produced after the air has passed between the curved portions of the screens and this construction will result in separating the lightest dust particles which have moved through the device adjacent the convex side of any one of the screens.

It is obvious that all of the screens may be of the construction having the extension 12, or they may be all of the construction without this extension, or they may be alternately arranged as desired.

After the device has been in service a period of time and has collected a sufficient quantity of dust particles the door 10 of Fig. 2 may be opened and the frame and screens removed and then cleaned and replaced or a substitution may be made of a clean frame and screens for the one removed, after which this one may be cleaned and substituted at the next change.

It is to be noted from the above that my cleaner is particularly adapted to be mounted at a point in the conduit where there is a change in direction of the conduit; that my cleaner does not increase the frictional resistance to the fluid flow at this point, but rather assists the fluid in making the change of direction of movement; that the centrifugal force set up in the change of direction of movement is utilized to force the dust particles against one or the other of the removing screens; and that even after the screens have collected their full capacity of dust, there is no material restriction to the free flow of the air through the device.

Having thus fully described my invention, I claim:

1. In a cleaner the combination of a conduit arranged at an angle, a housing at the angular portion of the conduit, a frame removably mounted in the casing, and screens carried by the frame.

2. In a cleaner the combination of a conduit, a housing forming part of the conduit, a frame removably mounted in the housing,

and a plurality of screens carried by the frame for collecting dust particles from a moving column of fluid.

3. In a cleaner the combination of a conduit, a housing forming part of the conduit, a frame removably mounted in the housing, a plurality of curved slots in the frame, and a curved screen mounted in each slot for collecting dust particles carried by a moving column of fluid.
